ATTORNEYS!

Patented Feb. 3, 1925.

UNITED STATES PATENT OFFICE.

OLE EVINRUDE, OF MILWAUKEE, WISCONSIN.

MOTOR PROPELLER.

Application filed May 19, 1921, Serial No. 470,998. Renewed September 15, 1924.

To all whom it may concern:

Be it known that I, OLE EVINRUDE, a citizen of the United States, residing at Milwaukee, in the county of Milwaukee and

5 State of Wisconsin, have invented certain new and useful Improvements in Motor Propellers, of which the following is a specification, reference being had to the accompanying drawing, forming a part thereof.

10 This invention relates more particularly to outboard motor propellers comprising internal combustion engines for use on boats of various kinds, particularly small or light craft such as row boats, canoes, etc.

15 Its main objects are to utilize the propeller post for conducting and discharging the exhaust from the motor or engine below the surface of the water, and incidentally for housing the transmission connections 20 between the engine and propeller wheel; to provide for locking the rudder swung forward against or close to one side of the propeller post for convenience in transporting the motor propeller as a unit when detached 25 from a boat; to provide an adjustable yielding hinge or pivot connection between the motor propeller and a boat on which it is mounted, which will permit the propeller to swing rearwardly and upwardly and clear 30 obstructions which it may encounter and which would or might otherwise break or injure it and its supporting and driving connections; and generally to improve the construction and operation of motor propellers of the type to which the invention 35 relates.

40 It consists in the construction, arrangement and combination of parts as herein-after particularly described and pointed out in the claims.

In the accompanying drawing like characters designate the same parts in the several figures.

45 Figure 1 is a side elevation partly in vertical medial section in a fore and aft plane, of a motor propeller embodying the invention; Fig. 2 is a rear elevation of the same; Fig. 3 is a side elevation of the steering and rudder locking head in connection with associated parts, showing the rudder swung forward against or close to the propeller post and locked in that position; Fig. 4 is a similar view showing the steering head in section and raised out of engagement with 50 the rudder; Figs. 5, 6 and 7 are horizontal

sections on the lines 5—5, 6—6 and 7—7 respectively, Fig. 1; and Fig. 8 is an enlarged inverted plan view of the steering head and associated parts.

55 Referring particularly to Figs. 1 and 2, a typical internal combustion engine, in the present case comprising two oppositely and horizontally disposed cylinders 1 and an intermediate crank case 2, is shown. An exhaust manifold, pipe or conduit 3 is bolted to the rear side of the cylinders 1 in communication with the exhaust ports thereof.

60 A hollow propeller supporting post, muffler and transmission housing 5, bolted or attached at the upper end to the crank case 2 and exhaust conduit 3 of the engine, is provided adjacent its lower end with a gear case 6 and with bearings 7, 8 and 9, for a propeller shaft 10 and transmission shaft 11. The shafts 10 and 11 are connected by 65 bevel gears 13 and 14, enclosed in the case 6, and at its upper end the shaft 11 is connected with the crank shaft of the engine 70 in the usual or any suitable manner (not shown).

75 A propeller wheel 16, mounted on the rear end of the shaft 10 has its hub formed with an annular exhaust passage 17, concentric therewith and registering at its front end with an exhaust outlet opening 18 in the 80 rear side of the post 5. The passage 17 is contracted adjacent its rear end to prevent the spreading of the exhaust gases discharged therefrom and their interfering with the proper operation of the propeller 85 blades, and it is provided with oblique or inclined vanes 19, adapted when the propeller wheel is rotated, to draw water and gases from the hollow post and muffler 5 and forcibly discharge the same from the 90 rear end of the hub, and thus assist in the propulsion of the boat on which the motor propeller is mounted.

95 A bracket 21, comprising clamps 22, which are provided with thumb screws 23 for detachably fastening it on the back, a gunwale or other part of a boat, is formed or provided with transversely aligned frictional pivot ears 24, which are connected by 100 bolts 25, as shown in Figs. 1 and 7, with corresponding frictional pivot ears 26, formed or provided on the crank case 2 of the engine, so as to permit the propeller wheel 105 with the supporting post 5 and the engine from which it is suspended, to be swung 110

rearwardly and upwardly for beaching the boat, clearing obstructions or traversing shallow water. The bolts 25 are held against turning in the bracket 21 by engagement of the bolt heads with lugs 27 on the ears 24, as shown in Fig. 7.

Between the ears 24 and 26, friction washers 28 of fiber or other suitable material, are interposed, and the pivot bolts 25 are 10 threaded and provided with nuts 29 for varying the frictional engagement of the ears with each other or the washers 28 between them, so as to hold the motor propeller in proper working position under 15 normal conditions and at the same time to allow the lower end of the post 5 with the propeller wheel to yieldingly swing rearward and upward to clear obstructions which would or might otherwise break or 20 injure the apparatus.

Between the nuts 29 and the ears 24, washers 30 are interposed and loosely keyed on the threaded ends of the bolts, as shown in Fig. 7, to prevent the loosening of the 25 nuts by the swinging of the motor propeller on its pivot connections with the bracket 21.

An adjustable stop screw 32, threaded in a lug 33 on the bracket 21, by engagement with the crank case 2 or an associated part 30 of the engine, limits the forward swing of the motor propeller on its pivot connections with the bracket 21, affords means for adjusting the post 5 to a vertical position according to the inclination of the part of 35 the boat on which the clamp 21 is mounted, and resists the forward thrust of the propeller wheel against the lower end of the post.

Lugs 35, on the pivot ears 26, by engagement 40 with a cross piece of the bracket 21, limit the rearward and upward swing of the motor propeller on its pivot connections with the bracket.

A rudder 37 is pivoted to vertically aligned lugs 38 and 39 on the rear side of the post 5 and the lower end of a guard 40 extending from the lower end of the post below the propeller wheel. A vertically shiftable tiller or steering head 42, 45 provided with cross arms 43 for the attachment of steering ropes, chains or wires, is pivotally mounted on the rear side of the post 5 above and in alignment with the pivot connections of the rudder with the post.

As shown in Figs. 1, 3, 4 and 8, the head 42 is formed with ears 44 and 45, in which a vertical pivot pin 46 is secured. The pin 46 is fitted to turn and slide lengthwise in 50 a lug or sleeve 48, which may be conveniently formed on a flange or plate 49 of a pump barrel or cylinder 50, and bolted or fastened therewith to the post 5. The ear 45 or the lower end of the head 42, is angular or 55 has a straight edge on the front side, in a

vertical plane parallel with the tiller arms 43, as shown in Fig. 8, and is formed with grooves 52 and 53 of different depths intersecting each other in alignment with the pivot pin 46, and adapted to engage with 70 the upper end of the rudder, as shown in Figs. 1, 2 and 3.

A spring 55, interposed between the lug 48 and the ear 45, yieldingly holds the head 42 with either of its grooves 52 or 53 in 75 engagement with the rudder, as shown in Figs. 1 and 3, and permits the head to be drawn upwardly out of engagement with the rudder, as shown in Fig. 4, to permit swinging the rudder from operative to inoperative position, or vice versa.

The shaft 11 is provided with a cam 57, which engages with and operates the pump plunger 58 for circulating cooling water through the cylinder jackets of the engine. 85 A suction pipe 60, leading upwardly from an opening in the rear side of the post 5 through the muffler chamber, supplies water to the pump.

The discharge of the pump is connected 90 in the usual or any suitable manner with the cylinder jackets, for instance by a branching pipe 59, and the spent cooling water is discharged from the upper parts of the jackets, for instance by pipes 61, as 95 indicated by dotted lines in Fig. 1.

A deflector 62, is provided in the exhaust inlet to the muffler chamber in the post 5 above the pump barrel 50, to prevent the direct impact of the exhaust gases against, 100 and the overheating of, the pump.

The post 5 is extended in a fore and aft direction to resist the strains to which it is subjected, and to afford a muffler chamber of sufficient capacity, and is preferably 105 formed on the front side with a central vertical strengthening rib or fin 64, which with the wheel guard 40 below the post, and the oblong shape of the post, as shown in Fig. 6, in front of the propeller wheel, smoothly 110 cleaves the water without interfering with the effective operation of the wheel.

In the operation of the motor propeller, when the engine is started and the propeller wheel is rotated, water which has entered and risen in the muffler chamber, is immediately drawn and expelled therefrom through the passage 17 in the wheel hub by the action of the vanes 19, which then operate to expel the exhaust gases discharged 115 into the muffler chamber from the engine, to relieve the engine of back pressure and to assist in the propulsion of the boat.

For running in shallow water and for 120 beaching the boat, the post 5 with the propeller wheel may be swung rearwardly and upwardly on the pivot bolts 25, with or without slackening the nuts 29.

In case an obstruction is encountered by 130 the post 5 or wheel guard 40, which would

or might break or injure the apparatus, the post with the propeller wheel will yieldingly swing rearward and upward on its adjustable friction pivot connections with 5 the bracket 21 and clear the obstruction.

For convenience in transporting or carrying the motor propeller when it is removed with the bracket 21 from a boat, the rudder 37 is disengaged from the deep groove 52 10 in the head 42 by lifting the head, as shown in Fig. 4, and then swinging it forward against or close to the post, as indicated by dotted lines in Figs. 2, 5 and 8, in which position it is locked and held by engagement with the shallow groove 53 and by the engagement of the angular ear 45 with the flange or plate 49, as shown in Fig. 3.

Various modifications in the construction and arrangement of parts of the apparatus 20 may be made without departure from the principle and scope of the invention as defined in the following claims.

I claim:

1. In a motor propeller the combination 25 with an internal combustion engine, of a propeller wheel suspended therefrom and having an exhaust passage extending through its hub adjacent its axis, and a conduit connected with the exhaust of the engine and having an opening registering with the passage in the propeller hub.

2. In a motor propeller the combination 35 with an internal combustion engine, of a hollow post attached at its upper end to the engine in communication with the exhaust of the engine, and provided adjacent its lower end with an exhaust opening, a propeller shaft mounted in the lower end of the post and projecting rearwardly therefrom, a propeller wheel fixed on said shaft and having an exhaust passage extending through its hub and registering with the exhaust opening in the post, and a transmission shaft geared at its lower end with 40 the propeller shaft and connected at its upper end with the engine.

3. In a motor-propeller the combination 50 with an internal combustion engine of a propeller wheel having an annular exhaust passage extending through its hub and a conduit connecting said passage connected with the exhaust port of the engine.

4. In a motor-propeller the combination 55 with an internal combustion engine of a propeller wheel having an annular exhaust passage extending longitudinally through its hub concentrically with its axis and connected at its front end with the exhaust conduit of the engine, said passage being 60 provided obliquely to the axis of the propeller wheel with a vane adapted with the rotation of the wheel to force the exhaust

gases from the engine rearwardly through the wheel hub.

5. In a motor-propeller the combination 65 with an internal combustion engine of a propeller wheel suspended therefrom and operatively connected therewith, the hub of the wheel having a co-axial annular exhaust passage extending longitudinally through it and connected at its front end with the exhaust conduit of the engine, said passage having an obliquely disposed vane for inducing a rearward flow therein when the wheel is rotated and being contracted to- 70 wards its rear end.

6. In a motor-propeller the combination 75 with an internal combustion engine, of a hollow post attached to and depending from the engine in communication at its upper end with the exhaust port of the engine and provided adjacent its lower end with a rear- 80 wardly directed exhaust outlet opening, a propeller shaft carried by the lower end of the post, a propeller wheel mounted on said shaft and having an exhaust passage ex- 85 tends longitudinally through its hub and communicating at its front end with the outlet opening in the post adjacent the propeller shaft, and transmission gearing connecting the propeller shaft with the engine.

7. In a motor-propeller the combination 90 of a propeller supporting post, a rudder pivoted to the rear side of the post, and a vertically shiftable steering and locking 95 head pivotally connected with the post in alignment with the pivot axis of the rudder and provided in its lower end with intersecting grooves of different depths for en- 100 gagement with the upper end of the rudder, said head having a part adapted in an ele- 105 vated position to engage with a part on the post to hold the head and rudder against turning when the rudder is swung forward close to the post and engaged with the shal- low groove.

8. In a motor-propeller the combination 110 of a propeller supporting post, a rudder pivoted to the rear side of the post, a verti- 115 cally shiftable steering and locking head pivotally connected with the post in align- 120 ment with the pivot axis of the rudder and having an angular lower end formed with intersecting grooves of different depths for engagement with the upper end of the rudder, a spring tending to shift the head down- 125 ward, and a projection on the post with which the angular end of the head engages to prevent its turning when the rudder is swung forward and engaged with the shal- lower groove.

In witness whereof I hereto affix my signature.

OLE EVINRUDE.
